UNITED STATES PATENT OFFICE.

ADELBERT R. CLIZBE, OF PLYMOUTH, INDIANA.

OIL BURNER.

Application filed June 16, 1924. Serial No. 720,152.

The object of my invention is to provide a simple and effective construction of oil burner particularly well adapted for use in heating stoves and furnaces, and the invention consists in the features of novelty hereinafter described, illustrated in the accompanying drawings and particularly pointed out in the claims at the end of this specification.

10 Figure 1 is a view in central vertical section through an oil burner embodying my invention. Figure 2 is a view in horizontal section on line 2—2 of Fig. 1. Figure 3 is a view in central vertical section on line 15 3—3 of Fig. 1.

My improved burner is shown as inclosed within a cylindrical wall A of the fire box of a stove or furnace, this fire box being of any suitable approved construction. In the 20 preferred embodiment of the invention, the burner comprises a cast metal base portion B having a laterally projecting flange b extending to the wall A, this base B being supported in any suitable manner, as by rods B', that extend upward from the bottom of the 25 stove or furnace and fit within sockets formed in the bosses b' depending beneath the base B.

The base B is formed with a concavo-convex combustion chamber B² open at its top and having the upper surface of its base portion b² flat, and formed, if desired, with a central raised portion b³. At opposite sides of the combustion chamber B² are 30 formed the air inlet ports b⁴, the walls of which are preferably cast integral with the body of the base B, and preferably the inner portions of the walls of these inlet ports b⁴ are formed with reduced portions over which 35 fit the depending tubular inlet portions c of the mixing chamber C. This manner of connecting the mixing chamber C with the base portion B enables the parts to be conveniently assembled and to be readily separated when it becomes necessary to clean 40 them. Between the inlet portions c of the mixing chamber C is formed a tubular outlet c' that opens above the center of the combustion chamber B². Beneath this outlet c' is placed a deflecting cone D that is 45 preferably formed as a separate part set loosely upon the flat base portion b² of the combustion chamber. The deflecting cone D resting loosely within the combustion chamber, 50 can be adjusted to the most effective position for spreading the mixed vapors issuing

downwardly through the outlet port c'. By forming this cone as a separate part, its upper surface can be ground or smoothly finished so as to more effectively serve to 60 uniformly spread the burning gases and render the cone less liable to become foul than if its surface were left as a rough casting.

Above the mixing chamber C and preferably cast integral therewith is a vaporizer E that is formed with a shallow rectangular chamber, the edges of which project laterally or outwardly beyond the walls of the mixing chamber and hence into the path 70 of the hot flaming gases as they rise from the combustion chamber B². A supply pipe F for the oil opens into the bottom of the vaporizing chamber E near one end and upon the floor of the vaporizing chamber E 75 is formed a rib or baffle e. This rib or baffle e extends along the floor of the vaporizing chamber E at a slight distance from the outer walls thereof, the rib or baffle e being of such shape as to cause the oil issuing 80 through the supply pipe F to pass lengthwise over the floor of those portions of the vaporizing chamber that project laterally above the combustion chamber and are hence subjected to the greatest heat. A break or 85 open space e' in the rib or baffle e permits any unvaporized portions of the oil, after it has traversed the floor of the vaporizing chamber, to pass (as indicated by the arrows Fig. 2) on to that part of the floor of the 90 chamber E inclosed by the rib or baffle e and thence into a pocket or depression E' that is formed in the bottom of the vaporizing chamber E. Through the vaporizing chamber E and its pocket or depression E' 95 passes a vapor pipe G, the lower portion of which is provided with a small discharge orifice g through which the vaporized oil from the chamber E will be ejected. This vapor pipe G is shown as provided with one 100 or more ports g' formed in its walls at a point or points approximately in line with the floor of the vaporizing chamber E. The pipe G has threads upon its outer lower portion which engage the threaded opening in the bottom of the pocket or depression E', hence the vapor pipe G can be adjusted to any desired position and can be readily removed for purposes of replacement or 105 cleaning. By thus extending the vapor pipe G through the depression or pocket E', danger of the vapor pipe becoming clogged 110

is avoided and any solid matter within the vaporizing chamber will tend to accumulate in the pocket E', from which it can be easily cleaned out when the vaporizing pipe G is removed.

The upper open end of the vapor pipe G extends into a cap or chamber E² the lower end of which is exteriorly screw threaded to engage the threaded wall of an opening 10 formed in the top of the vaporizing chamber E. When the cap or chamber E² is removed, the vapor pipe G can be readily adjusted or withdrawn. Preferably, the ends 15 of the vaporizing chamber E are formed with holes that are closed by removable screw plugs e⁴ and the removal of these screw plugs permits the ready cleaning of the chamber E.

From the foregoing description it will be 20 seen that when oil is admitted through the inlet pipe F to the vaporizing chamber E, it will be caused by the rib or baffle e, to flow along those parts of the floor of the chamber E that project outwardly from the mixing 25 chamber C and as these laterally projecting parts of the mixing chamber are exposed to the greatest heat from the combustion chamber, the vaporization of the oil will be most effectively secured. From the vaporizing 30 chamber the oil passes through the vapor pipe G downwardly into the outlet port e' of the mixing chamber, where it is mingled with the incoming air as it is forced downwardly upon the upper face of the deflecting 35 cone C within the combustion chamber B².

Having thus described my invention, what I claim as new and desire to secure by Letters Patent is:—

1. An oil burner of the character described comprising a combustion chamber, a mixing chamber located above said combustion chamber and having an outlet for delivering vapor to the combustion chamber, and a shallow vaporizer above said mixing 40 chamber having a vapor pipe with its discharge end arranged opposite said outlet of the mixing chamber, said vaporizer having a bottom rib spaced from its surrounding wall and provided with a break, a small central depression and a removable cap in its upper wall opposite the upper end of said vapor pipe and depression.

2. An oil burner of the character described comprising a combustion chamber, a mixing chamber having an outlet for delivering vapor to the combustion chamber, a vaporizer having a discharge passage for vapor arranged in the outlet adjacent said combustion chamber, and a deflecting cone 45 formed separate from and arranged within and loosely upon the bottom of said combustion chamber beneath said discharge passage for adjustment relative thereto.

3. An oil burner of the character described comprising a combustion chamber, a

mixing chamber located above said combustion chamber and having an outlet for delivering vapor to the combustion chamber, and a vaporizer above and extending across said mixing chamber and having a discharge 70 tube for vapor arranged opposite the outlet of the mixing chamber, said vaporizer being provided with a reduced depending bottom pocket with a reduced threaded bottom opening in which the tube is threaded and an oil 75 delivery pipe, said tube extending centrally down through the pocket in spaced relation to the surrounding wall thereof.

4. An oil burner of the character described comprising a combustion chamber, a mixing chamber located above said combustion chamber having oppositely disposed air inlets and fitting the top of the combustion chamber at its surrounding wall to provide a concentric central tubular outlet depending 80 into the combustion chamber, and a vaporizer integral with and the bottom wall of which is formed by the top of the mixing chamber and provided with a reduced depending bottom depression, an oil delivery pipe leading into the vaporizer, a vapor discharge pipe extending down through the bottom of the depression, said vaporizer having a continuous rib projecting upwardly from its bottom wall in spaced 85 relation to its lateral wall and the discharge pipe for causing the oil to flow along that part of the floor of the vaporizer exposed to the greatest heat from the combustion chamber and having an opening 90 through which the oil flows at a point remote from the oil supply means and over the floor of the vaporizer within said rib to the discharge pipe.

5. An oil burner of the character described comprising a combustion chamber, a mixing chamber located above said mixing chamber and forming a cover for the combustion chamber with a central tubular outlet extending into the combustion chamber for delivering vapor to the combustion chamber, and a vaporizer above said mixing chamber having a baffled relatively flat bottom wall with a depending central pocket extending down into the mixing chamber to collect sediment and a small vertical vapor pipe extending from said vaporizer down through and below said pocket for closing the bottom of the pocket discharging vapor in the outlet of the mixing chamber.

6. An oil burner of the character described comprising a combustion chamber, a mixing chamber located above said combustion chamber and having an outlet for delivering vapor to the combustion chamber, and a vaporizer above said mixing chamber having its floor provided with a small depression forming a pocket closed at the bottom and with a vapor pipe passing down

through the bottom wall of said depression and centrally in spaced relation to the wall thereof and provided at its lower end with a vapor discharge orifice.

5 7. An oil burner of the character described comprising a combustion chamber having a surrounding wall and air inlets, a mixing chamber located above the combustion chamber and having a surrounding 10 wall resting on the wall of the combustion chamber and continuations of the air inlets resting on the aforesaid inlets, the mixing chamber having a curved inwardly extending tubular outlet for delivering vapor to 15 the combustion chamber and depending into the latter, and a vaporizer above said mixing chamber having a discharge passage for vapor arranged opposite said outlet of the mixing chamber.

20 8. An oil burner of the character described comprising a combustion chamber having a surrounding wall and air inlets, a mixing chamber located above the combustion chamber and having a surrounding 25 wall resting on the wall of the combustion chamber and continuations of the air inlets resting on the aforesaid inlets, the mixing chamber having a curved inwardly extending tubular outlet for delivering vapor to 30 the combustion chamber and depending into the latter, a vaporizer above said mixing chamber having a discharge passage for vapor arranged opposite said outlet of the mixing chamber, a cone on the bottom of the 35 combustion chamber beneath the outlet, and a removable cap in an opening at the top wall of the mixing chamber over the discharge passage, said vaporizer having open-

ings at its ends, and removable plugs for closing said openings. 40

9. In combination with a firebox wall, a base fitting the same, a concave-convex combustion chamber with a relatively concave bottom wall and a top wall of inverted U-shape cross-section forming a central tubular 45 outlet, a mixing chamber resting on the base and combustion chamber for delivering vapor to the combustion chamber through the outlet, a vaporizer having a discharge passage for vapor arranged adjacent said combustion chamber, a raised portion on the bottom of the combustion chamber and a deflecting cone formed separate from and loosely arranged upon the bottom of the combustion chamber over the raised portion 50 and beneath the discharge passage. 55

10. An oil burner of the character described comprising a combustion chamber formed as a casting and with inlet passages at its sides, a mixing chamber resting thereon and located above the combustion chamber, said mixing chamber having outlets extending into the combustion chamber for delivering vapor thereto and having inlet portions coinciding with and fitting reduced portions of the inlet passages at the sides of the combustion chamber, and an elongated vaporizer extending diametrically across the mixing chamber and having a vertically adjustable and removable discharge tube for vapor extending into the outlet of the mixing chamber, there being an opening in the top of the vaporizer over the discharge tube and a cap over said opening. 60 65 70
